CLAIM

The ornamental design for an automatic faucet with mated housing, as shown and described.

DESCRIPTION

FIG. 1 is a front elevational view of an automatic faucet with mated housing showing our new design;

FIG. 2 is a top plan view thereof;

FIG. 3 is a right side elevational view thereof, left side elevational view being a mirror image thereof;

FIG. 4 is a rear elevational view thereof; and,

FIG. 5 is a bottom plan view thereof.

The broken lines in the figures are for illustrative purposes only and form no part of the claimed design.
